Attorneys.

UNITED STATES PATENT OFFICE.

EMIL RITZ, JR., OF CINCINNATI, OHIO, ASSIGNOR TO WALTER J. FRIEDLANDER, OF CINCINNATI, OHIO.

QUICK-THROW ELECTRIC SWITCH.

Application filed January 15, 1920. Serial No. 351,591.

To all whom it may concern:

Be it known that I, EMIL RITZ, Jr., a citizen of the United States, and a resident of the city of Cincinnati, in the county of Hamilton and State of Ohio, have invented certain new and useful Improvements in Quick-Throw Electric Switches, of which the following is a full, clear, and exact description, reference being had to the drawings, forming a part of this specification.

My invention relates to quick throw electric switches the special embodiment shown being for attachment to electric tools, and having a construction particularly adapted to this purpose.

In electric switches for quick throw operating on a longitudinal axis, the difficulty often encountered is that the operator by failing to operate them properly may exert force in spite of the mechanism a slight withdrawal of the switch bars from the live contacts, thereby causing a spark.

In my device the principle of operation is to retract the operating member in a direction toward the live contacts, thereby preventing the carrying of the contact member along with the spring member in its movement, until the immediate mechanism adjacent the switch contacts come into play.

I also provide a wedge form of operator for the movable switch member or members, which is of special construction so that a pressure in the nature of a lock is provided for the movable member when closed.

My objects and other advantages I accomplish by that certain construction and arrangement of parts to be hereinafter more specifically pointed out and claimed.

In the drawings,

Figure 1 is a central longitudinal section of the device on a vertical plane.

Figure 2 is a central longitudinal section at right angles to Figure 1.

Figure 3 is an enlarged elevation view of the switch with the cover broken away, the parts being in a position just before the quick throw takes place.

Figure 4 is a similar view to Figure 3 after the switch has thrown and showing the locking effect of the special shaped wedge.

The casing comprises a long tube 1, and a housing 2 at the forward end thereof, in

which the tube is socketed, said housing having a screwed on lid 3, on what may be termed the upper side thereof.

Within the tube is a long rod 4, which has a fixed collar 5 thereon, and slides at its rear end through a journal plate 6 in the tube. A spring 7 coiled around the rod between the collar and the plate tends, when compressed, to throw the rod forwardly.

A handle 8 in the form of a bell crank lever, is pivoted to the rod at 9 and to the tube casing at 10, so that pressing forward the exposed finger (which extends through a slot in the tube) will accomplish a movement of the rod rearwardly and compress the spring.

The rod passes at its forward end through another journal plate 11, and carries with in the housing 2 a bifurcated casting 12. In the two end bosses 13, 13, of the bifurcated portion of the casting, are located the sliding plungers 14, 14, each of which carries an anti-friction roller 15. The bosses are slotted on two opposite sides, and the plungers have pins 16 which extend out through the slots. A pair of springs 17, 17, secure the pins together and tend to draw the plungers with their terminal rollers, together, into space between the prongs of the casting.

A journal plate 18 is mounted across the center of the housing, and has slots 19 at both sides of the central opening. In this plate slides the movable switch closing member. This member comprises the switch plates 20, which when thrown into operation, extend across the electrical contacts 21, located in the end of the housing.

The switch closing plates are mounted on a rod 22, which slides in the journal plate 18, and carry an additional rod or long pin 23, which slides through the forward end 95 of the housing.

On the inner end of the rod is mounted the wedge plate 24, which is shaped like a diamond, with its rear ends beveled off as at 25. A ring 26 mounted loosely over the rod 100 ahead of the wedge plate, forms one bearing for a coiled spring 27, which bears at its other end on a collar 28 that is fast on the rod.

The operation of the switch is accomplished by moving the bifurcated member

so as to carry the rollers forward and back. The rollers ride over the edge of the wedge and a rearward movement of the wedge throws the switch forwardly, or vice versa for a forward movement thereof.

5 This operation results from the springs on the rollers which draw them together, so that they act on the wedge like an inclined plane.

10 As the bifurcated member is moved rearwardly thereby compressing the long spring in the tube member, the frictional pull of the rollers on the wedge tend to draw the wedge rearwardly also. This movement compresses the spring 27, since the ring at 15 the rear end thereof strikes the journal plate 18 and is thus held fast.

As shown in Figure 3 the rollers when 20 they reach the apices of the wedge or diamond, and start to pass it, will release the wedge with a jerk because of the spring 27 being under tension. Assisted by the forward throw of this small spring the rollers will force the switch member forcibly 25 forward into contact position.

When in contact position, as shown in Figure 4 the rollers will have moved to a 25 position behind the apices of the bevels. This will tend to lock the switch in contact 30 position against accidental jarring away and hence sparking.

The operator, it will be remembered, 35 throws the operating lever forward for throwing the switch into contact position thereby moving rearwardly the long rod, and compressing the spring. When he releases the spring the bifurcated member will be projected rapidly forward. As it approaches the apices of the wedge it will be 40 tending to force the contact points down against the switch points, but the moment it passes the apices it will jerk the contact points quickly away.

45 My mechanism thereby provides for a quick break and quick make, in a switch, which moves on a longitudinal axis. It also tends, during the progress of the movement forward or rearward, to preserve the contact members away from any sparking position, instead of exposing them to it.

50 It is not intended, because of my failure above to point out equivalent structures, to limit my claims that follow to the exact structure set forth.

55 Having thus described my invention, what

I claim as new and desire to secure by Letters Patent is:—

1. In a quick throw electric switch, the combination with a reciprocating member, of a movable switch closing element, a wedge member on the switch closing element, and resilient contractile means adapted to be positively moved over and straddle the wedge member under control of the reciprocating member, and adapted to move it into contact position, in a forward direction upon a rearward movement of said resilient means, and to move it out of contact position upon a forward movement of said resilient means with a spring on the reciprocating member adapted to be compressed on the rearward movement and to hasten the forward movement of the reciprocating member, and a spring on the switch closing element adapted to be compressed by the force of closing the said element.

2. In a quick throw electric switch, the combination with a reciprocating member, of a movable switch closing element, a wedge member on the switch closing element, and resilient contractile means adapted to be positively moved over and straddle the wedge member under control of the reciprocating member, and adapted to move it into contact position, in a forward direction upon a rearward movement of said resilient means, and a spring on said movable switch member adapted to be compressed under the frictional pull of rearward movement of said resilient means.

3. In a quick throw electric switch, the combination of a movable switch member, a diamond-shaped piece thereon, a bifurcated element moving in the path of said diamond-shaped piece, contractile spring roller means on the bifurcated element, bearing against said diamond shaped piece, and means for moving said bifurcated element, comprising a rod, a spring about said rod, and means acting against said spring to compress it upon movement of said rod to throw the switch member into contact position, whereby rapid action in a reverse or switch-opening position is assured, and a spring intermediate the diamond shaped piece and the switch member adapted to be compressed when the diamond shaped member is projected to switch closing position.

EMIL RITZ, JR.
